INSULATOR MOUNTING

Lorell J. Schilling, Brookfield, Ill., assignor to
Babson Bros. Co., a corporation of Illinois

Application September 4, 1941, Serial No. 409,582

4 Claims. (Cl. 174—158)

This invention relates to an insulator mounting, and more particularly to improved means for supporting an insulator particularly designed for an electric fence.

One feature of this invention is that it provides improved means for supporting the wire of an electric fence; another feature of this invention is that the insulator mounting or bracket is particularly strong and particularly well locked to the insulator; a further feature is that the bracket is adapted to be attached to a number of different types of posts; other features and advantages of this invention will be apparent from the following specification and the drawing, in which:

Figure 1 is a side elevational view of the mounting bracket, the position of the insulator thereon being indicated in dotted lines; Figure 2 is a front elevational view of the showing of Figure 1; Figure 3 is a top plan view of the same arrangement; Figure 4 is a view of the sheet metal blank from which the bracket is made; Figure 5 is a detail sectional view showing the method by which the insulator and bracket are locked together; and Figure 6 is a horizontal sectional view showing the method by which the bracket is attached to a metal fence post.

Electric fences for holding stock or protecting fields have become increasingly popular in the past few years. These fences generally comprise only a single strand of wire, normally insulated from the ground, and are supplied with shocking current of high voltage and low amperage. When an animal contacts the fence the circuit is completed to ground and the animal receives a shock causing it to shy away from the fence. After several such experiences the animals usually become trained to stay away from the fence altogether.

The big advantages of such fences are, of course, the fact that they normally require only a single wire, and can be used with light widely spaced posts, so that movement of fences is greatly facilitated. This is particularly important in connection with rotation of pasturage and the like, where it may be desirable to move a fence every month. Even where fences are only moved once a year, the labor costs are greatly reduced by using an electric fence rather than the old-fashioned type of fence relying on its strength to stop the animals. In order that these normally open circuit fences shall not be inefficient and waste energizing current it is necessary that they be well insulated from ground. Pre-

vious efforts in this direction have involved many disadvantages and defects.

My present invention comprises mounting means particularly designed to support line insulators for electric fences. The mounting means may be used on either wooden or metal posts, and the arrangement is such that they may be very easily and quickly assembled in proper relation to the insulators, and the two locked together.

Referring now to the particular embodiment of my invention illustrated herewith, a mounting bracket indicated in general as 10 is shown attached to a wooden post 11 by nails 12 and 13 driven through openings 14 and 15 in the bracket.

15 The bracket comprises three principal portions, one portion 16 being adapted to lie against the fence post; another portion 17 extending at right angles therefrom; and a third portion 18 extending upwardly at right angles to the latter portion, this last mentioned portion 18 being formed in a channel or U-shape as may be best seen in Figure 3.

This upstanding channel portion of the bracket is adapted to support a generally cylindrical line 20 25 insulator 19 provided with circumferential grooves 20 and 21, the upper groove 20 being adapted to support a fence wire, so that the fence wire is insulated from ground and may be appropriately electrically energized. As may be best seen in Figure 3, the fence wire 22 may be held in place in the upper groove by a short connecting or holding wire 23. The particular outer configuration of the generally cylindrical insulator is quite important, and the particular form I 30 disclose here is very efficient in shedding water and is so designed as to practically eliminate breakage from strain on the fence wire, particularly where the fence wire is at a slight angle to its proper position in the groove. This insulator 35 shape will not be described in detail here, since it was fully described in my earlier filed copending application, Serial No. 353,729, filed August 22, 1940, and since it is the subject matter to which my Design Patent 126,722, which issued April 22,

45 1941, is directed. It should be particularly noted, however, that the bottom of the insulator is provided with a quite deep depression or upwardly extending pocket 24, to lengthen the leakage path from the bottom of the skirt of the insulator to the mounting bracket on the dry underside; and that the bottom of the skirt has been provided with a number of projections 25 which provide drip points and which enable the entire underside of the insulator to be properly glazed.

50 55 In manufacturing the brackets blanks of the

character shown in Figure 4 would be first stamped out of flat sheet metal, preferably metal of a thickness in the neighborhood of 14 gauge. The same operation which stamped out the shape shown in Figure 4 would also stamp out the previously mentioned holes 14 and 15, the hole 26, the notch or slot 27, and cut three sides of a tongue 26, preferably also forming it out at an angle of about 30°, as shown in dotted lines in Figure 1. By appropriate forming dies the end 29 would then be turned up at right angles to the portion 16, the portions 16 and 17 bent at right angles to each other along the line 30, and the channel portion formed by first making a right angle bend along the dotted line 31, and then another right angle bend along the dotted line 32. The bracket would then be in condition to be assembled with the insulator, and this could be readily done by slipping the insulator over the channel-shaped portion. In order to enable this to be done the insulator 19 is provided with a substantially square axial opening 33 adapted to snugly receive the channel-shaped portion, as may be best seen in Figures 3 and 5, this opening being provided in one wall with a pocket 34, the bottom 35 of the pocket providing a shoulder adapted to cooperate with the previously mentioned tongue 28 of the bracket.

Since the initial bend of the tongue does not cause it to extend beyond the space occupied by the channel-shaped portion, the insulator can be easily slipped down into position, the parts then being as illustrated in Figure 1. It will be understood that the assembly of the insulator and its bracket is performed at the factory, and that at the time the bracket and insulator were as shown in Figure 1 they would not normally have been fastened on a post, being shown in this position merely for convenience of illustration of the final way in which my invention will be used. When the insulator and bracket are in this relation a small square punch is inserted up into the opening, within the confines of the channel-shaped portion, and the tongue forced out to the position shown in Figure 5, the end of the tongue then engaging the shoulder 35 and firmly locking the insulator and bracket together. This locking operation can be very simple and conveniently performed by a punch with its end at the desired terminal angle of the tongue 28, that shown in Figure 5, since it is only necessary to stand the insulator and bracket upside down on a work table, insert the punch, and tap it once with a hammer to lock the parts together. The assembled insulators and brackets are then shipped to the farmer and used as illustrated in Figures 1, 2 and 3.

The provision of the two holes 14 and 15 enables the mounting bracket to be rigidly nailed or screwed to a wooden post with the channel portion in the desired upright position or, if preferred, in a horizontal position. In addition, the provision of the hole 26 and the slot 27 enables the bracket to be conveniently and quickly attached to a light iron or steel post of the kind finding favor with electric fences, as shown in Figure 6. If reference is had to this figure it

will be seen that the portion 16 is adapted to lie along the front face of a T-shaped metal post 36, and to be held in place thereon by a wire 37 extending through the opening 26 and the slot 27. The wire may be easily put in the position shown, and then drawn taut by twisting its ends 38 with a pair of pliers.

The embodiment of my invention disclosed above will be seen to provide a particularly rugged and efficient insulator and mounting bracket assembly which is adapted to be used in any desired position, and which may be conveniently fastened to either conventional wooden or metal fence posts. The provision of a channel-shaped insulator supporting portion provides great strength; and the particular locking arrangement insures against subsequent separation of the insulator from its bracket.

While I have shown and described certain embodiments of my invention, it is to be understood that it is capable of many modifications. Changes, therefore, in the construction and arrangement may be made without departing from the spirit and scope of the invention as disclosed in the appended claims.

I claim:

1. Apparatus of the character described, including: a generally cylindrical insulator having an axial rectangular opening therein having a pocket in one wall providing a shoulder; and a metal supporting member having a channel portion adapted to be at least partially snugly received in the opening, said portion being provided with a tongue adapted to be forced out into engagement with said shoulder to lock the insulator on the supporting member.

2. A member for supporting an insulator having an opening therein, including: a portion adapted to be mounted on a post or similar support; a portion extending at right angles thereto; and a U-shaped channel portion at right angles to the second mentioned portion, this U-shaped portion being provided with an angularly extending tongue and being adapted to be received in said opening and locked therein, the entire member being a single unitary piece of initially flat sheet metal.

3. Apparatus of the character described, including: an insulator having an opening therein provided with a shoulder; and a soft sheet metal supporting member having a portion channel shaped in cross section and at least partially received in a snug fit in the opening, said opening having a shape corresponding to that of the channel shaped portion, the channel shaped portion being provided with a tongue portion forced out into engagement with said shoulder and remaining in engagement therewith to lock the insulator on the supporting member.

4. Apparatus of the character claimed in claim 3, wherein the channel shaped portion is open at the end extending out of the insulator and is large enough to provide room for the insertion of a tool to force the tongue out into engagement with the shoulder.
